LPA(57) **CLAIM**

The ornamental design for a socket extension drive as shown and described.

DESCRIPTION

FIG. 1 is a top, front perspective view of a socket extension drive showing my new design;

FIG. 2 is a bottom, rear perspective view thereof;

FIG. 3 is a front elevation view thereof, wherein a rear elevation view is an identical image thereof;

FIG. 4 is a right-side elevation view thereof, wherein a left-elevation view is an identical image thereof;

FIG. 5 is a top plan view thereof;

FIG. 6 is a bottom plan thereof;

FIG. 7 is an enlarged top plan view thereof; and,

FIG. 8 is an enlarged bottom plan view thereof.
